SIDES FOR RAILWAY FREIGHT CARS

Gabriel Madland, Chicago, Ill., assignor to The Youngstown Steel Door Company, Cleveland, Ohio, a corporation of Ohio

Application December 15, 1952, Serial No. 325,977

7 Claims. (Cl. 105—409)

This invention relates to sides for railway freight cars and is concerned more particularly with such sides built as a unit and serving as replacements for deteriorated or obsolete sides of existing freight cars.

It is an object of this invention to provide sides for railway freight cars which shall include extension members so constructed and arranged as to serve as tension members as well as members for closing the space between the existing side sills of the cars and the side sheathing.

A further object is to provide sides for railway freight cars embodying extension members which shall be mechanically continuous substantially from end to end of the car and which shall obviate openings or indentures heretofore required in such extension members.

A further object is to provide sides for railway freight cars embodying posts, brackets for directly connecting the posts to the existing side sills of the cars and extension members wherein the brackets shall lie above the webs of the extension members.

A further object is to provide sides for railway freight cars embodying posts, brackets for directly connecting the posts to the existing side sills of the cars and extension members having upwardly and outwardly extending webs wherein the brackets shall lie above and be secured to the webs.

A further object is to provide sides for railway freight cars embodying extension members adapted to be secured to the existing side sills of the cars so that the webs of the extension members are disposed below the top of the side sills.

A further object is to provide sides for railway cars embodying extension members so disposed and arranged relative to the existing side sills of the cars as to be adapted to carry means for supporting door tracks.

A further object is to provide sides for railway freight cars embodying posts, brackets for directly connecting the posts to the existing side sills of the cars and extension members wherein identical post connection brackets can be used.

A further object is to provide sides for railway freight cars embodying posts, brackets for directly connecting the posts to the existing side sills of the cars and extension members wherein the brackets below the door opening formed in the sides shall serve as supports for threshold plates.

A further object is to provide sides for railway freight cars embodying posts, brackets for directly connecting the posts to the existing side sills of the cars and extension members wherein the parts are so arranged that the connecting brackets are simplified and their cost reduced.

Other objects of the invention will become clear as the description thereof proceeds.

In the drawings forming part of this specification:

Fig. 1 is a fragmentary elevation of a side for railway freight cars embodying the instant invention.

Fig. 2 is a horizontal section taken on line 2—2 of Fig. 1.

2

Fig. 3 is a vertical section taken on line 3—3 of Fig. 1. Fig. 4 is a vertical section taken on line 4—4 of Fig. 1. Fig. 5 is a vertical section taken on line 5—5 of Fig. 1. Fig. 6 is a vertical section taken on line 6—6 of Fig. 2.

Referring to the drawings the numeral 10 designates generally a side embodying the instant invention and adapted to be applied preferably as a unit to the existing side sill 11 of a railway freight car. The side 10 embodies a side plate 12 which as is customary extends substantially from end to end of the car. The side 10 embodies a plurality of door posts and intermediate posts. One of these door posts is indicated at 13 and one of the intermediate posts is shown at 14. The construction and arrangement of the door posts and intermediate posts is well known and the disposition of the door posts in order to define a door opening 15 is also well known to those skilled in the art.

The upper ends of the door posts and intermediate posts are secured to the side plate either by welding or by riveting. At their lower ends the door posts and the intermediate posts are directly connected to the existing side sill 11 of the car by means of simplified and identical brackets 16. Each of these brackets is formed of a pair of plate members 17 and 18 which are turned outwardly to provide flanges 19 and 20 by means of which the brackets are secured to the side sill 11 preferably by rivets 21 and 22. At its outer end each of the plates 17 and 18 is formed to provide upstanding flanges 23 and 24 secured as by means of rivets 25 and 26 on opposite sides of the inwardly extending flange 27 of the Z-shaped door post 13 and inwardly extending web 28 of the Z-shaped intermediate posts 14.

Metallic sheathing 29 is secured to the web 30 of the door posts and to the outer flange 31 of the intermediate posts. By virtue of the construction hereinabove described the metallic sheathing and the posts lie in outwardly spaced relationship to the side sill 11. To close this space an extension member 32 is utilized. This extension member embodies a downwardly extending flange 33 secured to the side sill 11 as by means of rivets 34, an upwardly and outwardly extending web 35 and an upwardly extending flange 36. The latter flange lies on the outside of the web 30 of the door posts and is overlapped by the sheathing 29. This flange is secured as by means of rivets such as 37 to the sheathing and the door posts. Similarly the upwardly extending flange 36 lies on the outside of the flange 31 of the intermediate posts and is overlapped by the sheathing 29. This flange is secured to the sheathing and to the intermediate posts as by means of rivets 39 and 40. Securement of the brackets to the inclined web 35 is obtained preferably by means of welding the lower edges of the bracket plates 17 and 18 to the web 35. For this purpose the lower edges of the plates 17 and 18 are inclined similarly to the web 35 and are welded to the web as indicated at 41.

Additional securement is obtained between the door posts 13 and the extension member 32 by means of a gusset 42. The gusset 42 is angular in cross section and embodies a flange 43 secured as by means of rivets 44 and 45 to the upstanding flange 36 of the extension member 32 and a flange 46 which is similarly inclined and secured to the web 35 as by means of rivets 47. The gusset 42 also embodies an inwardly extending flange 48 which is secured to the flange 27 of the door post as by means of rivets 49. As is shown more clearly in Fig. 1 of the drawings the flange 48 of the gusset 42 is inclined downwardly and rearwardly as indicated at 50 so as to be spaced from the flange 27 of the door posts and the upstanding flange 24 of the brackets 16 secured to the door posts. By reason of the described form of the gusset 42 the brackets which secure the door posts to the side sill can be made identical with the brackets which secure the intermediate posts to the side sill.

It will be apparent from the foregoing description that the upwardly and outwardly inclined web 35 of the extension member 32 is disposed below the top of the side sill 11. It will also be apparent that the brackets 16 which directly connect the posts to the side sill 11 are positioned entirely above the extension member 32 so as to be concealed by the extension member. Moreover, the inclination of the web 35 permits the extension member to serve as a tension member in addition to its function as a closure member so that it will carry a portion of the tension stresses imposed upon the posts. Also the welding of the inclined web of the extension member to the brackets serves to obtain a unity of action of these parts.

Brackets 51 are utilized within the door opening 15. These brackets are shaped somewhat differently from the brackets 16 and are formed of plates 52 and 53. The plate 52 is formed with a flange 54 at its inner end by means of which it is secured to the side sill 11 as by means of rivets 55. At its outer end the plate 52 is formed with a flange 56 through which it is secured to the upstanding flange 36 as by means of rivets 57. The upper edge of the web 58 of the plate 52 is formed with a substantially horizontal portion 59 and an upwardly and outwardly inclined portion 60. The lower edge of the plate 52 is inclined upwardly and outwardly similarly to the web 35 and is secured to the web as by means of welding 61.

The plate 53 is similar in its structure to plate 52 and is accordingly provided with inner and outer flanges 62 and 63 which are secured respectively to the side sill 11 and to the upstanding flange 36 of the extension member 32 as by means of rivets 64 and 65. The upper and lower edges of the bracket plate 53 are shaped similarly to the upper and lower edges of the bracket plate 52. The plate 53 is so arranged relative to the plate 52 that the web 66 of plate 53 preferably abuts the web 58 of plate 52.

The brackets 51 serve not only to reinforce the upstanding flange 36 in the door opening but also act as supports for a threshold plate 67 lying in the door opening. The threshold plate embodies a horizontal flange 68 which extends across and is welded to the upstanding flange 36 and which along its outer edge is formed with a depending flange 68a disposed in outwardly spaced relationship to the flange 36 and terminating above the door track 69. The plate 67 extends inwardly of the upstanding flange 36 and at its inner edge is formed with a depending flange 70 which is spaced inwardly of the flange 36 and which terminates in a horizontal flange 71 resting upon and welded to the upper edge of the brackets 51 as indicated at 72. In the illustrated embodiment of the invention the horizontal flange 71 serves as a support for the outer edge of floor boards 73 while the inner depending flange 70 serves as an abutment for the floor boards. Beyond the door posts a combined grain board and floor board support 74 is employed. Each of these boards is grained as indicated at 75 so as to provide a shoulder 76 upon which the outer edge of the floor boards 73 are supported and an abutment 77 for the outer edge of the floor boards. The abutment 77 of the combined grain board and floor board support members and the inner depending flange 70 of the threshold plate are aligned longitudinally of the car so that all of the floor boards used whether in the door opening or beyond the door opening are of the same length.

The track 69 is formed of an angle member which is arranged with one flange 78 in horizontal position and the other flange 79 in vertical position and depending from the flange 78. A plurality of track brackets 80 are secured to the underside of the horizontal flange 78 as by means of rivets 81. To support the track as illustrated a plurality of track bracket supports such as 82 are employed. Each of these brackets is formed of a bent plate which provides a downwardly and inwardly inclined flange 83 secured to the underside of the web 35 of ex-

tension member 32 as by means of rivets 84. The track bracket support 82 also provides a vertical depending flange 85 to which the track brackets 80 are secured as by means of rivets 86. The flanges 83 and 85 are reinforced by means of a plate member 87 which is welded to these flanges.

It will be apparent that numerous changes and modifications in the details of the invention will be clear to those skilled in the art. It is intended, therefore, that all such changes and modifications be comprehended within this invention which is to be limited only by the scope of the claims appended hereto.

I claim:

1. A replacement carside unit for railway freight cars adapted to be secured to a side sill of a said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web and a depending flange adapted to be secured to the side sill, and metallic brackets secured to said posts and adapted to be secured to the side sill for fastening said posts directly to the side sill, said brackets being secured to said web.

2. A replacement carside unit for railway freight cars adapted to be secured to a side sill of said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web and a depending flange adapted to be secured to the side sill, metallic brackets secured to said posts and adapted to be secured to the side sill for fastening said posts directly to the side sill, said brackets lying entirely above the web of said extension member and means securing said brackets to said web.

3. A replacement carside unit for railway freight cars adapted to be secured to a side sill of a said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web and a depending flange adapted to be secured to the side sill, and metallic brackets secured to said posts and adapted to be secured to the side sill for fastening said posts directly to the side sill, said brackets comprising pairs of plates, the lower edges of said plates having a slope similar to the slope of said web of said extension member and being welded thereto.

4. A replacement carside unit for railway freight cars adapted to be secured to a side sill of a said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web disposed below the top of the side sill and a depending flange adapted to be secured to the side sill, metallic brackets secured to said posts and adapted to be secured to the side sill for fastening said posts directly to the side sill, said brackets lying between the top of the side sill and said web of said extension member and means securing said brackets to said web.

5. A replacement carside unit for railway freight cars

adapted to be secured to a side sill of a said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web and a depending flange adapted to be secured to the side sill, metallic brackets secured to said posts and adapted to be secured to the side sill for fastening said posts directly to the side sill, said brackets lying entirely above and being secured to said web of said extension member and door track supporting members secured to the underside of said web.

6. A replacement carside unit for railway freight cars adapted to be secured to a side sill of a said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web and a depending flange adapted to be secured to the side sill, gussets secured to said door posts and to said upstanding flange and web of said extension member and having a portion offset longitudinally from said door posts, identical metallic brackets secured to said intermediate and door posts and adapted to be secured to the side sill for fastening said posts directly to the side sill, said door post brackets being secured to said door posts adjacent to the offsets in said gussets and means securing said brackets for said intermediate and door posts to said web of said extension member.

7. A replacement carside unit for railway freight cars adapted to be secured to a side sill of a said car comprising a metallic side plate, metallic intermediate and door posts adapted to be disposed outwardly of the side sill, means securing the upper ends of said posts to said side plate, metallic sheathing secured to said side plate and said posts, a longitudinally continuous metallic extension member having an upstanding flange secured to said posts and sheathing, a downwardly and inwardly sloping web disposed below the top of said side sill and a depending flange adapted to be secured to the side sill, metallic brackets secured to said posts and adapted to be secured to the side sill for fastening said posts directly to the side sill, metallic brackets secured to said upstanding flange between said door posts and adapted to be secured to the side sill, the portion of said latter brackets adjacent to the side sill lying below the side sill, means securing all of said brackets to said web, and a threshold plate having a horizontal flange projecting outwardly beyond and welded to said upstanding flange and a portion extending downwardly from said horizontal flange and welded to said portion of said second-mentioned brackets lying below the side sill.
